ALBERT CLEMENS, OF LOUISVILLE, KENTUCKY.

DEVICE FOR DELIVERING MATERIAL FROM A CONTAINER.

1,072,427.

Specification of Letters Patent.

Patented Sept. 9, 1913.

Application filed December 7, 1911. Serial No. 664,510.

To all whom it may concern:

Be it known that I, ALBERT CLEMENS, a citizen of the United States, residing at Louisville, in the county of Jefferson and 5 State of Kentucky, have invented a new and useful Device for Delivering Material from a Container, of which the following is a specification.

My invention relates to improvements in 10 devices for distributing and applying material from a container, in which the material is spread in small quantity over a surface adapted to receive it, to be applied from this surface in the way desired.

15 The object of my improvement is to provide an easily portable arrangement so constructed that there is no danger of spilling the supply of the material, that the amount applied to the surface will be even and not 20 excessive, and that the whole will furnish a ready means of applying the material to its desired object. I attain these objects by the mechanism illustrated in the accompanying drawing in which—

25 Figure 1 is a perspective view of the entire structure, Fig. 2 a top view of the same, having the top of the inner chamber removed so as to show the internal structure, Fig. 3, a vertical section of the structure adjacent the movable rod.

Similar letters refer to similar parts throughout the several views.

The rectangular box, container or reservoir A, having a top A¹, a bottom A², and 35 ends A³ and A⁴, is provided with a slit A⁵, here shown in the end A⁴, while at the opposite end a hole A⁶ is provided. A guide-rod A⁷ is fixed longitudinally in the box A. A carrier B, here in the form of a ribbon or 40 strip of flexible material, furnishing a surface adapted to hold the material, is of such cross section that it passes easily, but with a close fit, through the slit A⁵. This ribbon, tongue or carrier is shown somewhat longer 45 than the box A, so that when it is drawn into the interior of the box to a position in which the inside end is near the end A³, a portion of the carrier is still projecting outside of the slit A⁵. It is obvious that in this 50 position the projecting portions may be grasped and the carrier drawn through the slit.

In the construction illustrated, the inner end of the carrier is provided with a metal 55 shoe B¹ preferably extending clear across, this shoe narrowing to a sharp edge. To

this shoe is attached a sleeve B², adapted to run on the guide rod A⁷. A movable rod C is provided, adapted to pass through the hole A⁶, its outer end being provided with a 60 knob C¹ and its inner end bearing a sleeve C² which runs on the fixed rod A⁷. The sleeve B² is of such form as to act as a stop to prevent the carrier B from being wholly withdrawn through the slit A⁵. The sleeve 65 C² is of such form and so adjusted with reference to the fixed rod A⁷ on which it slides and the sleeve B² that the sleeve C² is nearer the slit A⁵ than the sleeve B² and the two cannot pass. It is evident that when the carrier B is withdrawn from the box A as far 70 as it will go, it may be drawn back into the box by merely pulling out the rod C, the sleeve C² sliding along the fixed rod A⁷, drawing with it the sleeve B² and the whole 75 carrier B to which the sleeve B² is attached. When this operation is accomplished, and the carrier B drawn inside the box A as far as it will go, the rod C may be pushed back into the box, so as not to project. 80

The box A is provided with an opening A⁸ and suitable cover D¹ therefor; the opening affording a means of introducing into this box A whatever material is to be distributed on the carrier and applied therefrom. In the form shown, a pad of 85 resilient material A⁹ is placed along the interior portion of the slit, which operates to prevent leakage of material through the slit when the carrier is withdrawn. 90

The invention is applicable to many uses, for example may be utilized as a cosmetic applying device. The cosmetic is introduced into the box, and coming in contact with the carrier, adheres thereto. The carrier being 95 withdrawn, and being impregnated with the cosmetic, may be applied to the skin. When this is complete, the carrier may be withdrawn into the box until again needed. It is evident that if desired the whole device 100 may be made of such size as to be easily carried about, for use whenever convenient.

The carrier is made of material suited to the character of application desired, the construction described consisting of a double 105 thickness of chamois skin, reinforced by an intermediate layer of linen B³.

The shoe B, mentioned above, gives needed stiffness to the carrier, and being narrowed to an edge, prevents the crowding or 110 accumulation of the contents of the container when the carrier is withdrawn back

into the container. As shown in the drawing this edge is in the plane of that surface of the carrier which is closest to the wall of the box A, so that the beveling tends to throw such material as tends to accumulate in front of the shoe, back into the bed of the box.

It is to be observed that the slit employed in my invention is so designed that practically no leakage of material is possible as the carrier passes through it, and that the walls of the slit will remove from the carrier, as it moves outwardly, any excess of material adhering thereto. The entire device constitutes one which may be inverted or used in any position, and is so designed that non-solid material, such as a powder or semi-liquid, may be used therein, without being subjected to any special treatment or preparation. The length of the carrier which is in contact with the material to be distributed, renders impregnation more complete than is possible where the carrier is rolled or comes in contact with the material at certain points only. The absence of any spring operated mechanism makes it possible to pull the carrier out as far as may be desired, where it will set without fastening or any added device, and since the carrier is available and perfectly loose at the end outside the box, without springs tending to draw it back, application to the surface desired is much easier than where it is necessary to fasten the outer end of the carrier in order to keep it from retreating back into the carrier. The structure described furnishes a means by which the carrier may be withdrawn from the box to any desired extent, and conveniently used in that position without further fastening; and by which the carrier remains flat and unrolled throughout its entire length within the container while being moved integrally or as a whole, such length within the container being in contact with the material. It also makes available for application practically the entire length of the carrier, so that there is no material portion which comes in contact with the contents of the container, which cannot be withdrawn and used. The device makes it possible to use, if desired, a material for the carrier which does not permit of being rolled or bent over. It is to be noted that the return of the carrier into the chamber is easily controlled by the operator's hand, and may be effected to any desired extent.

A further advantage of this device is that when the carrier strip is withdrawn to its full extent, being prevented from complete withdrawal by the projecting stop, no portion of the said carrier is exposed to the material within the container. In the devices in which some portion of the strip must remain within the chamber, exposed to

contact with the material, it is evident that the portion which remains inside uses up the material, without ever being available for application, and that the adhering material to this inner part of the carrier strip, gradually tends to clog it up and interfere with smooth operation.

I claim as new and desire to protect by Letters Patent the following:

1. In a device for distributing and applying material from a container a structure forming a reservoir chamber, a carrier normally in contact with the contents of the chamber and contained by the chamber, but adapted to move as a whole in its own plane so that a part thereof is exposed outside the chamber, a stop projecting from the inner end of the said carrier and operating to prevent its entire withdrawal. 75
2. In a device for distributing and applying material from a container, a structure forming a reservoir chamber, a carrier normally in contact with the contents of the chamber, but adapted to slide to a position outside the chamber, and means for returning the carrier to normal position in contact with contents of reservoir chamber, the whole being so constructed that the material is loosely confined by the walls of the chamber, and that the portion of the carrier which at any time is within the chamber is at all parts exposed to contact with the contents of the chamber, and free from rolling. 80
3. In a device for distributing and applying material from a container, a supply chamber provided with a narrow opening, a pliable strip designed to slide therethrough without material leakage from the chamber to a position such that no part of said strip remains exposed to the contents of the supply chamber, and means whereby the strip may be drawn into the chamber in such manner that its entire length within the chamber will be exposed to the contents of the same. 100
4. In a device for distributing and applying material from a container, a box forming a chamber and having a slit at one part of its walls and a hole at another, a movable carrier normally lying within the chamber except where a portion projects through the before mentioned slit, the said carrier being adapted to be partially withdrawn through said slit, and means operable through the before-mentioned hole in the box by which the inner end of said carrier, together with the rest of the carrier, may be moved in a direction away from the slit, thereby tending to return said carrier into the chamber 115 from a withdrawn position. 120
5. In a device for distributing and applying material from a container provided with a slit and adapted to serve as a reservoir of material, a strip normally within 130

said chamber, and in contact with the contents, but with one end projecting outside through said slit, the said strip being provided with a stop-projection at its inner end, 5 and adapted to be so completely withdrawn that no part remains within the reservoir except the end bearing the stop projection, together with means for restoring the strip to its normal position, by rectilinear 10 placement of the entire strip.

6. In a device for distributing and applying material from a container, a strip of fabric designed to carry the material, made up of layers of chamois skin with stiffening 15 fabric between, adapted to pass back and forth through an opening in said container.

7. In a device for distributing and applying material from a container, a carrier designed to move in a slit in the wall of said 20 container, and a movable rod adapted to engage the inner end of said carrier whereby the said carrier may be moved through the wall of said container.

8. In a device for distributing and applying material from a container, having a 25 reservoir, a carrier with its greater portion normally within said reservoir but projecting through an opening therein, a movable rod movable into and out of the container 30 and provided with means for engaging said carrier and a fixed rod in the container adapted to serve as guide for the carrier and the movable rod.

9. In a device for distributing and applying material from a container, having a 35

reservoir, a carrier adapted to slide back and forth through the wall of the reservoir, a sleeve fixed to the carrier, a rod movable through the wall of the reservoir and provided with a sleeve on its inner portion, and 40 a rod fixed to the reservoir walls, on which both sleeves are adapted to slide.

10. In a device for distributing and applying material from a container, a reservoir, a carrier normally in contact with the 45 contents of the reservoir, and contained by the reservoir, but capable of being almost completely withdrawn therefrom, said carrier being placed close to one of the walls of said reservoir, means for returning said 50 carrier to the normal position, and a shoe on the inner end of said carrier, said shoe being beveled so that the edge is even with that side of the carrier which is nearest the wall of the reservoir. 55

11. In a device for distributing and applying material from a container, having a reservoir, a carrier normally in contact with the contents of the reservoir, but capable of being partially withdrawn therefrom, a 60 movable rod penetrating the wall of the reservoir, a projection on said movable rod and another on said carrier so designed as to engage one another, when the rod is drawn outward.

ALBERT CLEMENS.
